(57) **CLAIM**

The ornamental design for a device for extricating mud-stalled vehicles, as shown and described.

DESCRIPTION

FIG. 1 is a perspective view of a device for extracting mud-stalled vehicles showing our new design;

FIG. 2 is a top view thereof;

FIG. 3 is a bottom view thereof;

FIG. 4 is a first side view thereof;

FIG. 5 is a second side view thereof;

FIG. 6 is a third side view thereof;

FIG. 7 is a fourth side view thereof; and,

FIG. 8 is a perspective view thereof with the device in an upright condition.

In the drawings, the broken lines depict a vehicle that form no part of the claimed design.
